UNITED STATES PATENT OFFICE.

WILLIAM NEHRING, OF CINCINNATI, OHIO, ASSIGNOR TO THE QUEEN CITY
MALLEABLE IRON COMPANY, (LIMITED,) OF SAME PLACE.

ANNEALING-FURNACE.

SPECIFICATION forming part of Letters Patent No. 247,943, dated October 4, 1881.

Application filed July 16, 1881. (No model.)

To all whom it may concern:

Be it known that I, WILLIAM NEHRING, of Cincinnati, Hamilton county, Ohio, have invented a new and useful Improvement in Annealing-Furnaces, of which the following is a specification.

My invention is more particularly designed for the production of malleable cast-iron.

It is well known that the labor of putting the articles to be annealed into and getting them out of the furnace in the customary plan is attended with much delay and difficulty, and that, while within the furnace, some of the larger articles are insufficiently annealed, while other articles, becoming overheated, are liable to sag and to become welded together, and, besides injuries received from these causes, are with difficulty removed from the furnace.

With the object of economizing both material and labor, and withal producing better work, I have so constructed my improved furnace that a full charge of articles to be annealed can be inserted simultaneously, and, when in the judgment of the furnace-man sufficiently annealed, can be as promptly removed. To accomplish this I have constructed the bottom and front of the oven or furnace on a strong iron frame-work mounted on wheels and movable toward and from the stationary portions along a rail-track like a truck. Except for the largest articles, the objects to be annealed are placed in crucibles or boxes, which boxes are stacked on the floor of said movable portion, which portion is then pushed into the furnace proper, of which the floor of the truck then constitutes the bottom, and of which the wall at one end of the truck constitutes the closed door. This having been done, the joint between the fixed and movable portions is sufficiently closed by means of brick.

In order to regulate and direct the heat to different parts of the oven, I construct my flues in several branches, one or more of which are capable of being wholly or partially closed at discretion of the attendant.

In the accompanying drawings, Figure 1 is a longitudinal fore-and-aft section of an annealing furnace or oven embodying my inven-

tion. Fig. 2 is a section on the line *x x*, Fig. 1. Fig. 3 is a front elevation with the truck in position. Fig. 4 is a section on the line *y y*, Fig. 2. Fig. 5 is a side elevation of my truck. Fig. 6 is a partially - sectioned elevation of a modification of my furnace, designed for the larger class of articles. Fig. 7 is a section on the line *z z*.

A represents an arched vault of masonry, open at both ends. This vault is divided into two unequal compartments by a pier or partition, B, which, stretching transversely from side to side, reaches nearly to the ceiling. Of these compartments the smaller compartment is, at its upper part, occupied by a fire-place or furnace proper, C, having a grate, D, coke-shelf E, mouth F, and door G. For this fire-place the upper part of wall B does duty as fire-bridge. Through the passage H, above the said fire-bridge, the products of combustion escape into the larger compartment aforesaid.

The wall B has a flue or uptake, I, which communicates at or near its lower part on the front side with a series of flues, J, that communicate with like flues, K, in the bed or floor l of the truck L. The uptake I discharges by flue N into a suitable chimney. (Not shown.) The flues K, near their front ends, communicate by short down-takes M with the said larger compartment, which compartment, in conjunction with said truck, constitutes my oven proper, Z. The flues K extend preferably to the extreme front of the truck, so as to form openings K', in the manner represented, and each is supplied with a movable plug or stopper, Q, which, being pushed rearward or drawn forward, serves to close or open the respective down-takes, and thus to regulate and direct the heat to particular parts.

Rising vertically from the front edge of the truck-floor is a wall, P, which, when the truck is driven home, serves as the front wall of my oven, and also does duty as its door.

Ventilators or cooling-inlets Q in the truck-wall are closable by means of doors R, by partially or wholly opening of which air may be admitted, either to assist combustion or to aid

in regulating the heat, either generally or locally, as may be deemed necessary.

The doors R are preferably provided with mica windows S, to enable inspection from time to time of the interior of the oven.

T are the truck-wheels, resting upon a track or tramway, U.

V is an offset in the wall B, to receive the luting-bricks.

10 The dimensions of the truck-wall are preferably just sufficiently less than the interior of vault A to permit the introduction of luting bricks or tiles W.

X represents a cast-iron slab, upon which 15 are stacked the crucibles or boxes Y, which are charged with the articles to be annealed.

In the modification shown in Figs. 6 and 7 there are two parti-walls, B' B''. The smoke enters downtakes M' at mid-length of truck-20 floor, thence escaping through two sets of flues, K' K'', to the two uptakes I' I'', and the truck and tramway are so disposed as to give a motion in or out parallel with, instead of at right angles to, the parti-walls.

25 The modification, Figs. 6 and 7, although capable of use with crucibles, is chiefly de-

signed for articles of large dimensions, with which crucibles are not commonly employed.

Having thus described my invention, the following is what I claim as new therein and desire to secure by Letters Patent:

1. The combination, in an annealing-furnace, of the fire-place C, the parti-wall, with its uptake I, and the truck L, with its wall P and flues M and K. 35

2. The combination, with oven Z, whose floor and front are component parts, of a separable truck, L, the orifices Q and K' in said front and orifices M in said floor communicating with oven and with floor-flues K, respectively, 40 the said floor-flues discharging into flues J, leading to uptakes I within fire-bridge B, said orifices being provided with regulating doors or stoppers, the whole being arranged and operated substantially as set forth. 45

In testimony of which invention I hereunto set my hand.

WILLIAM NEHRING.
